United States Patent Office

Des. 216,245
Patented Dec. 9, 1969

216,245

SWIMSUIT OR SIMILAR ARTICLE

Edward H. Mohl, 5716 Woodbine Ave.,
Philadelphia, Pa. 19131

Filed Nov. 25, 1968, Ser. No. 14,642

Term of patent 14 years

Int. Cl. D2—01

U.S. Cl. D2—40

FIG. 1

FIG. 2

FIG. 1 is a front elevational view of a bathing suit or similar article, showing my new design, the back thereof being conventional and unornamented; and

FIG. 2 is a cross sectional view taken along line 2—2 of FIG. 1.

I claim:

The ornamental design for a swimsuit or similar article, as shown and described.
